[57] CLAIM

The ornamental design for a storage bin, as shown and described.

DESCRIPTION

FIG. 1 is a top perspective view of a storage bin showing our new design;

FIG. 2 is a top plan view of the storage bin of FIG. 1;

FIG. 3 is a front elevational view of FIG. 2;

FIG. 4 is a right side elevational view of FIG. 2; the left side being a mirror image thereof;

FIG. 5 is a rear elevational view of FIG. 2;

FIG. 6 is a bottom plan view of FIG. 2; and,

FIG. 7 is a perspective view similar to FIG. 1 with the storage bin in an open position.
